UNITED STATES PATENT OFFICE.

JOHN H. GILBAUGH, OF PORTLAND, OREGON.

CHIN-SUPPORT FOR DEAD PERSONS.

1,139,670.

Specification of Letters Patent. Patented May 18, 1915.

Application filed June 18, 1914. Serial No. 845,885.

To all whom it may concern:

Be it known that I, JOHN H. GILBAUGH, a citizen of the United States, and a resident of the city of Portland, county of Multnomah, State of Oregon, have invented a certain new and useful Improvement in Chin-Supports for Dead Persons, of which the following is a specification.

My invention relates to supports for holding the chin of a deceased person in natural position, until set in place by the muscular rigidity which usually for a time follows death, in order to avoid the face assuming an unnatural appearance. To this end, I have invented a simple support readily affixed on the head of a deceased person, and so arranged and adapted that it will not slip out of place. I furthermore make the band of my support of two members of resilient material, said members being fastened together at their inner ends by means permitting the band to be lengthened and shortened so that my device can be used on different profiles; and I also prefer to make the members of the band articulated, that is to say, of sections hinged together, so that my support may be folded into a compact convenient form when not being used.

The details of construction of my device are hereinafter fully set forth.

In the accompanying drawings: Figure 1 is a side elevation of my device, showing it as used in actual practice; Fig. 2 is a side elevation of the device as it appears when not in use; Fig. 3 is a left-end elevation of Fig. 2; Fig. 3^a is an enlarged detail of construction; and Fig. 4 is a side elevation similar to Fig. 2, but showing a modified construction.

In the device shown in Figs. 1, 2 and 3, *a* represents one member of the band of my support. This member is provided with a cupped chin plate *a'*, the edge of which is preferably slightly rolled, as at *a²*, to prevent possible marking of the chin. At the inner end of the member *a* is a longitudinal slot, *a³*, made with enlarged circular portions, *a⁴*. Furthermore, the member, *a*, has its end upturned, as at *a⁵*. The other member of the band is represented by *b*. This member is provided at its outer end with lateral arms *b'*, the extremities of which are turned down and formed with tooth-like projections, *b²*. On the inner end of the member *b*, and on the center line thereof, is

a stud *b³* and a transverse bar member *b⁴*. The stud *b³* is of such diameter as to fit the circular enlargements *a⁴*, and the transverse bar *b⁴* has a width slightly less and a length slightly greater than the slot *a³*.

In assembling my device, the section *b* is placed in transverse relationship to the member, *a*, so that the bar, *b⁴*, may enter the slot *a³*. The two sections are relatively rotated, until the stud *b³* is brought into alignment with one of the circular enlargements *a⁴* of the slot *a³*, whereupon the resilient qualities of the sections will cause the stud to spring into such circular enlargement.

To adjust the length of the device, the end of the section, *a*, is sprung outwardly by the thumb, being thrust under the upturned end *a⁵* of the member, *a*, (see broken lines of Fig. 2) and the two sections may be displaced longitudinally until the stud *b³* registers with another of the circular enlargements of the slot *a³*, thereupon said stud will spring into the enlargements and lock the band members against further longitudinal movement.

The use of my device will be readily seen by having reference to Fig. 1. The chin plate *a'* is placed under the chin of the person, and the lateral arm *b'* of the member *b* placed on the top of the head. The serrated edges *b²* will then grip the head and give the two points of support necessary to insure the required rigidity in the device, so that the support will not slip out of place. The curve of the resilient tensioned members will entirely clear the features and hold the chin firmly up in natural position until the muscles have set, when the support is to be removed.

In Fig. 4 I have shown my support as provided with hinges *a⁶*, *b⁶*, which allow my support to be folded together, as shown by the broken lines of that figure. The overlying lips *a⁷*, *b⁷*, serve as stops for the hinged members.

I claim:

1. A device of the character specified comprising a band made of two members; means fastening the inner ends of said members together but permitting the same to be longitudinally moved over each other, for lengthening and shortening the band; the extremities of one member being provided with lateral portions for bearing on the top of the head, the extremities of said portions

being made with tooth-like projections, and the extremity of the other member being made with a plate for bearing on the chin.

2. A device of the character specified comprising a band made of two articulated resilient members; means fastening the inner ends of said members together but permitting the same to be longitudinally moved over each other, for lengthening and shortening the band; the extremities of one member being provided with lateral portions for bearing on the top of the head, and the extremity of the other member being made with a plate for bearing on the chin.

15 3. A device of the character specified comprising a band made of two articulated resilient members; means holding the inner ends of said members in sliding engagement with each other, other means for locking 20 said ends together as adjusted; the extremities of one member being provided with lateral portions for bearing on the top of the head, the extremities of said portions being made with tooth-like projections and the 25 extremity of the other member being made with a plate for bearing on the chin.

4. A device of the character specified comprising a band made of two members; the

inner end of one band being made with longitudinal slots having enlargements spaced 30 apart; the companion inner end of the other member being made with a stud fitting said enlargements of said slots, and also having a transverse bar adapted for passing through the slot when longitudinally alined therewith.

5. A device of the character specified comprising a band made of two members; the inner end of one band being made with longitudinal slots, having enlargements 40 spaced apart, the companion inner end of the other member being made with a stud fitting the enlargements of said slots, and also having a transverse bar adapted for passing through the slot when longitudinally alined 45 therewith; the extremities of one member being provided with lateral portions for bearing on the top of the head, the extremities of said lateral portions being made with tooth-like projections, and the extremity of the other member being made with a plate for bearing on the chin.

JOHN H. GILBAUGH.
